US00D977297S

(12) **United States Design Patent** (10) Patent No.: **US D977,297 S**
 Anthony et al. (45) Date of Patent: ** Feb. 7, 2023

(54) OVEN	1,018,817 A *	2/1912	Farrell	A47K 10/22
(71) Applicant: SHARKNINJA OPERATING LLC , Needham, MA (US)				242/598.4
(72) Inventors: Joshua D. Anthony , North Billerica, MA (US); Nicholas Varjabedian , Middleboro, MA (US); Dan Kestenbaum , Brookline, MA (US)	1,021,413 A	3/1912	Koch	D19/86
	D55,266 S *	5/1920	Fuller	A47K 10/38
	2,222,951 A *	11/1940	Krueger	242/596.8

(57) CLAIM

The ornamental design for an oven, as shown and described.

DESCRIPTION

FIG. 1 is a perspective view of an oven, showing our new design;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The broken lines are shown for the purpose of illustrating parts of the article that form no part of the claimed design.
